[57] CLAIM

The ornamental design for a wet suit or similar article, as shown and described.

DESCRIPTION

FIG. 1 is a front and right side perspective view of a wet suit or similar article showing my new design as it would appear on a seated wearer;

FIG. 2 is a front elevational view thereof;

FIG. 3 is a left side elevational view thereof;

FIG. 4 is a left side elevational view as the suit would appear on a standing wearer.
